INTERNAL COMBUSTION ENGINE

Clarence H. Wiegman, Detroit, Mich., assignor
to Packard Motor Car Company, Detroit, Mich.,
a corporation of Michigan

Application July 21, 1930. Serial No. 469,403

11 Claims. (Cl. 123—179)

This invention relates to internal combustion engines and more particularly to engines of the compression-ignition type in which fuel is injected into the combustion chamber through a mechanism actuated by a moving engine part.

The invention has to do more particularly with the starting of engines of the character described in which fuel is injected at a pressure developed in accordance with the engine speed. With this type of engine, the degree of fuel atomization and the pressure at which the fuel is injected becomes less as the speed of the engine is reduced, and thus the fuel is not injected into the compressed air in the combustion chamber at a pressure or in an atomized condition conducive to easy starting when the crank shaft is being turned slowly by a source of external power.

An object of the invention is to regulate the timing, the pressure and atomization of liquid fuel injected into compressed air in the cylinders of a compression-ignition engine so as to promote combustion when the engine is being started.

Another object of my invention is to provide an internal combustion engine of the compression-ignition type in which manually controlled mechanism can be actuated to simultaneously retard the timing of the fuel injections and to increase the pressure produced by a moving part of the engine upon the fuel injected.

A further object of the invention is to provide a manual control for regulating the actuation of the fuel injection devices of a compression-ignition engine so that during starting, fuel charges will be injected into the combustion spaces when the compressed air charges are at substantially their highest compression, and under a pressure such that sufficient penetration occurs to quickly cause a thorough intermingling of the fuel mixture.

Still another object of the invention is to provide a manual control which can be actuated during the starting of an engine of the compression-ignition type to bring into action a faster moving fuel pump actuating cam mechanism at a later time in the compression stroke of the engine operation.

These and other objects of the invention will appear from the following description taken in connection with the drawings, which form a part of this specification, and in which:

Fig. 1 is a rear elevational view of a radial engine, partially broken away and partially in section to show a fuel injecting device and its actuating mechanism;

Fig. 2 is an elevational view showing the fuel

injection mechanism cams, with the faster cam in effective position and having made one rotation beyond the position shown in Fig. 1;

Fig. 3 is a sectional view of the engine taken on line 3—3 of Fig. 1;

Fig. 4 is a sectional view of the engine taken on line 4—4 of Fig. 3;

Fig. 5 is a fragmentary sectional view of the fuel injection mechanism associated with an engine cylinder.

Referring now to the drawings by characters of reference, 10 represents generally the crank case of a compression-ignition type of internal combustion engine from which nine air-cooled cylinders 11 extend radially, the cylinders being secured under compression around the wall of the crank case by rings, one of which is indicated at 12. The cylinders are formed with an integral dome 13 and secured upon each of the domes is a head 14. Each of the associated heads and domes is formed with a single Venturi passage 15 leading into the interior of the associated cylinder, such passages serving as both the air inlet and the exhaust outlet for the combustion chambers between the cylinder domes and the pistons 16. In order to control the passages 15, there is associated with each a valve 17 which is normally closed by a plurality of springs 18 and opened by conventional mechanism which includes a push rod 19 extending into the crank case.

A diaphragm, or internal wall 20 is secured within the crank case and is formed with a central opening in which is arranged a bearing 21 for supporting one end of the crank shaft 22, the crank shaft projecting axially through the crank case. Arranged in a relation substantially parallel to the diaphragm is a detachable rear wall 23 which closes the open end of the crank case, and detachably secured to the rear wall is a starting device, indicated generally at 24, which is preferably of the inertia type as illustrated in Patent No. 1,739,469, issued December 10, 1929, to R. P. Lansing. Such starting device is provided with a reciprocable jaw 25 which projects into the crank case in alignment with the rear end of the crank shaft, so that it can be moved manually into a driving relation therewith.

The engine illustrated is of the compression-ignition, or Diesel type, which operates on a four-stroke cycle, air charges being drawn into the cylinders through the passages 15 upon the suction strokes of the pistons, during which time the valves 17 are mechanically held open. The valves are next closed and the compression

strokes then occur, and during the compression strokes charges of liquid fuel or oil are injected into the air-compressed charges under a high pressure and in an atomized condition such that 5 the mixture thereof with the compressed air will form a readily combustible charge. There is associated with each cylinder a fuel injection device which consists generally of a nozzle portion 26 and a pump portion 27, the nozzle portion being 10 secured rigidly to the cylinder and arranged to project through the wall thereof so that the fuel charges can be injected directly into the interior of the cylinder.

Each nozzle consists of a barrel 28 having a 15 detachable end 29 which extends through the associated cylinder wall and is formed with a conical outlet opening in which the valve head 30 is associated. The valve stem 31 is arranged to be moved into engagement with the stop member 32 by a spring 33, and such stop member is adjusted to prevent the valve from entirely closing. The barrel 28 is formed with a downwardly extending neck portion which is provided with a passage 34 leading to the hollow chamber 20 in the barrel through which the valve rod extends. Such nozzle neck is screwed into the casing 35 of the associated pump unit and bears against a ring spacer 36 which maintains the pump barrel 37 in position within the casing 35, 25 there being a pair of spring-pressed valves 38 associated with the ring member and the barrel to prevent liquid fuel returning to the pump structure from the nozzle structure. A plunger 39 is arranged to reciprocate within the pump barrel 37 and a fuel inlet manifold 40 communicates with all of the pumps, there being unions 41 in the manifold structure associated one with each of the barrels, and ports 42 extend through the casing and the barrel to establish communication 30 between the fuel feeding manifold unions and the interior of the valve. Such ports are controlled by the position of the plunger, so that when the plunger uncovers the ports 42 liquid fuel is moved into the pump barrel and the 40 nozzle completely filling the chambered portions therein. The pump plungers are moved in their injection strokes by mechanism, which will be hereinafter described, and during such movement they close the ports 42, their stroke after 45 closing such ports determining the quantity of fuel which is displaced from the nozzle into the cylinder.

It will be seen that the speed of the plunger movement determines the degree of pressure at 55 which the fuel charge is injected. The effective stroke of the plungers will force fuel past the valves 31 and from the nozzles in a manner such that the fuel charges are directed into the cylinders in a conical spray. The air inlet passages 60 are formed and arranged so that they cause rotation of the air in the cylinders and such rotation continues during the following compression stroke of the piston, the fuel charges being sprayed into such compressed rotating air 65 charges.

The degree of fuel atomization and the extent of the pressure at which it is injected determine the degree of the intermingling of the oil with the air and, therefore, it is necessary that there 70 be sufficient injection penetration and atomization to cause a uniform distribution of the fuel in the compressed air charges if efficient engine operation is to result. It is also necessary that the atomization and penetration of the air 75 by the fuel oil be of a certain character if com-

bustion is to be attained when the cylinders are cold, as they are when starting. With the type of injection mechanism described, in which the fuel pressure varies in accordance with the crank shaft speed, there is difficulty experienced when 80 turning the crank shaft at a slow speed in starting to produce a sufficient pressure behind the fuel charges because of the consequent slow movement of the fuel pumps which is not sufficient to cause the fuel atomization and penetration of the compressed air charges required to produce a mixture which will support combustion. 85

This invention has to do particularly with 90 mechanism for injecting fuel oil in an atomized condition and at a sufficient pressure to cause an intermingling with the compressed air in the cylinders such that ignition will readily result when the crank shaft is being slowly turned through the application of a starting device. To 95 this end, I utilize the regular fuel injecting mechanism for the normal running operation of the engine and provide an auxiliary actuating mechanism therefor which is effective only during the application of the starting mechanism to the 100 crank shaft. This auxiliary actuating mechanism is made effective manually and is placed in ineffective relation automatically when the starting device is released from the crank shaft. In carrying out such invention, I propose that the 105 liquid fuel charges will be injected, during the turning of the crank shaft by the starting device, at a pressure which will cause the fuel to penetrate substantially to the center of the cylinder and in a finely atomized condition so that 110 one rotation of the compressed air in the cylinder will cause a uniform distribution therein of the atomized liquid fuel.

Under normal running operation, crank shaft 115 actuated mechanism is provided for causing the pump plungers to move in their injection strokes, and such mechanism is returned to a position causing uncovering of the ports 42 by the coil spring 43. A fuel plunger push rod 44 extends through the crank case and has associated there- 120 with a lever 45 which is pivotally connected with a link 46 carried between a regulating ring 47 rotatably mounted within the crank case. The ring 47 can be actuated through the association of a tooth segment 48 with a rack 49 which is 125 fixed to the ring, the segment being rotated by means of the shaft 50 which is in turn actuated through suitable mechanism connected with the lever 51. Associated with each of the levers 45 is a slipper or rock lever, as shown at 130 52, 53 and 54, each being carried by individual shafts 55 supported by the diaphragm and the rear casing cover 23. The free ends of the rock levers are formed with a curved face against which the associated lever 45 is maintained by 135 means of the adjustable ring 47 and the connecting links 46, so that upon movement of the levers 45, lengthwise of the slippers, the effective stroke of the pump plungers can be simultaneously adjusted. 140

Arranged interiorly of the pivoted slippers 53, for actuating the same to cause an injection stroke of the pump plungers, is a cam 56 which is provided with four lobes 57, 58, 59 and 60. A cam 60' is formed with an internal gear 61 145 with which the gear 62 meshes, and this gear is mounted integrally on the same shaft with the gear 63 which is arranged adjacent the end wall of the casing. Meshing with the gear 63 is a gear 64 which is keyed to the rear end of the 150

crank shaft. This arrangement of gearing, just described, is related so that rotation of the crank shaft will cause rotation of the cam 56 in a direction opposite to that of the crank shaft and at one-eighth the speed of rotation thereof. The rotation of the cam 56 is such that upon each two revolutions of the crank shaft, the lobes 57, 58, 59 and 60 will cause one actuation of each of the nine slippers associated with the fuel injection mechanisms. The cam 60' is also provided with a series of four lobes 72, one of which is shown in Fig. 1, for actuating slippers 73, mounted on the shafts 55, with which the valve push rods 19 are associated so that during the suction and exhaust strokes of the pistons, the valves are held open thereby.

As before stated, I have found that with the fuel injection mechanism described, sufficient penetration of the compressed air charges in the cylinders and a desirable atomization of the fuel is attained during running operation of the engine under load to result in combustion, but when the crank shaft is being turned slowly by an auxiliary source of power, such as a starting device, the resulting cam rotation does not impart movement to the fuel injecting mechanism which will develop sufficient pressure to be exerted against the fuel charges to cause the required penetration of the air charges and sufficient atomization to support combustion. In order to secure this necessary fuel pressure and atomization, and to inject the fuel at a time during the air compression when the best efficiency will result, I provide an auxiliary mechanism for actuating the slippers associated with each of the injection devices, and to this end I provide each of the fuel mechanism slippers with an extended portion 74 so that they can be actuated by a single lobe cam 75 which is arranged to be driven with and at crank shaft speed. This cam, running at crank shaft speed, will move eight times as fast as the regular fuel actuating cam 56 and, consequently, will cause a much faster stroke of the pump plungers than would be caused by the cam 56, thus resulting in a highly increased pressure and an atomization beyond that which would be attained with the cam 56 in effective position when the crank shaft is turning at slow speeds. In addition, the cam 75 is arranged to cause an injection stroke of the plungers at a later time during the air compression stroke than that which is caused by the cam 56. The cam 75 is preferably arranged to cause fuel injections just shortly before the pistons reach the top of their compression strokes, while the cam 56 is preferably arranged during engine operation so that the fuel injections occur in a range between 40 to 20 degrees before the pistons reach top center on their compression stroke. I have found that when starting, this delay in timing and the provision of a pressure behind the fuel charge will cause a substantial penetration of the compressed air charges in a well atomized condition, which materially assist the quick starting of engines of the compression-ignition type operating on liquid fuel of low volatility, and as a result, very little turning of the crank shaft is required to cause combustion.

The cam 75 is secured to the crank shaft by screws 76. The cam 56 is provided with a hub portion 77 which extends rearwardly and upon which the hub of the cam 60' is rotatably mounted.

Only one of the fuel device actuating cams is effective at a time, and manually controlled

mechanism is associated with the cams 56 and 60' for regulating the position of the cam 56 angularly of the crank shaft so that either the cam 56 or 75 is effective. A control sleeve 78 is partially telescoped between a flange 79 extending rearwardly from the cam 60' and the rear end of the hub 77, such sleeve having peripheral helical teeth 80 which engage similar teeth formed interiorly of the flange 79. The front end of the sleeve is provided with helical splines 81 which mesh with helical splines 82 formed in the periphery of a coupling member 83. Such coupling member surrounds the rear end of the cam hub 77 and is provided with helically extending splines 84 which mesh with the helical splines 85 formed on the periphery of the rear end of the hub 77. A nut 86 is screwed upon the end of the crank shaft for axially retaining the coupling member 83.

In order to control the position of the sleeve 78, I provide a yoke 87 which engages therewith, such yoke being actuated by the rod 88 extending through the end wall of the casing. A stop member 89 is fixed to the rod and a spring 90 is arranged within a recess in the end wall to exert pressure against the stop member normally tending to cause movement of the yoke 87 to its rearmost position.

When the yoke and control sleeve 78 are in their rearmost position, as shown in Figs. 1 and 3, the cam 56 is disposed angularly upon the crank shaft and relative to the cam 60' so that the lobes thereon will be effective to actuate the fuel injection mechanism. The lobes 57, 58, 59 and 60 are of sufficient length such that they maintain the rocker levers, which they have actuated, in an elevated position until such time as the single lobe on the cam 75 has passed thereunder, thus making the cam 75 ineffective. As the cam 75 moves at crank shaft speed and in the same direction with the crank shaft, the timing is such that the rocker levers will be in a raised relation through association therewith of the cam 56 so that regardless of an eight times faster speed, the cam 75 will be ineffective. It will be remembered that the cam 56, when in this position, is arranged to actuate the rocker levers between 40 and 20 degrees before the pistons reach top center, depending upon the adjustment of the levers 45, while the starter cam 75 is fixed angularly on the crank shaft to be effective approximately ten degrees before the pistons reach top center on their compression strokes. It will also be seen that the cam 56 is driven from the cam 60' through the control sleeve 78 and the coupling 83 so that it will rotate in an integral relation therewith.

As the yoke 87 is moved forwardly through actuation of the rod 88, the helically splined association of the sleeve 78 with the flange 79 and the cam 60' will cause rotation of the sleeve and a similar rotation of the coupling 83 and of the cam 56, so that in this manner the angular position of the cam 56 upon the crank shaft will be changed to move the lobes thereon so that they will be moved to ineffective position as shown in Fig. 2, and preferably where they would be effective when the pistons reach top center of the compression strokes. With such control mechanism, the moving of the cam 56 angularly relative to the crank shaft into an ineffective position and holding the same in such relation, will make the cam 75 effective. As the cam 75 is rotating eight times faster than the cam 56, the speed at which the fuel injecting mechanism

is actuated will be materially increased over that which would result if the cam 56 were effective.

As before explained, the control sleeve 78 is normally in its rearmost position as shown in Figs. 1 and 3, and when it is desired to start the engine, the rod 88 is pushed forward moving the control sleeve 78 as far as possible, which will rotate the cam 56 angularly upon the crank shaft into an ineffective position, thus making the cam 75 effective. As the sleeve is moved axially, it will be caused to rotate because of the helically splined association with the cam member 60', the inertia of the elements geared with such cam member being greater than that of the cam member 56. The crank shaft has a jaw 91 at the end thereof which the starter jaw 25 is moved into engagement with and rotation is imparted to the crank shaft through this connection, with the control ring 78 in its forward position. During such relation, the cam 75 is rotating at such a speed that it will shield the slippers associated with the fuel injection mechanism from being actuated by the lobes on the cam 56. Rotation of the crank shaft by the starter, with the cam 75 effective, will cause a much higher pressure to be exerted against the fuel charges injected than if the cam 56 were effective, and with the crank shaft turning at a relatively slow speed, the pressure and atomization resulting from actuation of the fuel injection mechanisms by the cam 75 will cause the fuel charges to penetrate to substantially the central portion of the cylinders so that a homogeneous mixture with the compressed air rotating therein will occur within a very few degrees of the crank shaft rotation. In this manner, while the fuel charges are injected only ten degrees before top center of the compression strokes of the pistons, the proper mixing of the fuel with the air and combustion will occur before the pistons reach top center. This mechanism materially aids in the starting of a compression-ignition engine because the proper mixture of the fuel must be present in order to cause the initial explosions which will ultimately heat the cylinders sufficiently to produce self-ignition.

While I have herein described in some detail a specific embodiment of my invention, which I deem to be new and advantageous and may specifically claim, I do not desire it to be understood that my invention is limited to the exact details of the construction, as it will be apparent that changes may be made therein without departing from the spirit or scope of my invention.

55 What I claim is:

1. In a compression-ignition engine, a pressure injection device for introducing liquid fuel into compressed air charges in the engine, a crank shaft, a cam for actuating the injection device, an air valve actuating cam, a gear fixed to the injection device actuating cam, reduction gearing intermediate the crank shaft and the air valve actuating cam, an axially movable driving sleeve meshing with the gear fixed to the cam and having a helically splined association with the air valve actuating cam, said driving sleeve being movable axially to change the relation of the fuel injection device actuating cam angularly of the crank shaft, manually operable means for shifting the sleeve in one axial direction, and spring means opposing the manual movement of the sleeve.

2. In a compression-ignition engine, a pressure injection device for introducing atomized liquid fuel into compressed air charges in the en-

gine, a crank shaft, a single lobe cam for actuating the device fixed to the crank shaft, a multiple lobe cam for actuating the device and rotatably associated with the crank shaft adjacent the fixed cam, an air valve actuating cam, a reduction driving mechanism between the crank shaft and the air valve actuating cam, a driving connection including a movable sleeve helically splined to the air valve actuating cam and geared to the multiple lobe cam, the movement of the sleeve relative to the cams causing the multiple lobe cam to be rotated to place the lobes thereof in effective or ineffective relation with the fuel device through operation in advance of or behind the fixed cam lobe respectively, means automatically urging the sleeve into one extreme position, and a manually actuated means for shifting the sleeve into its other extreme position.

3. In a radial cylinder compression-ignition engine, a pressure injection device associated with each cylinder for introducing atomized liquid fuel into compressed air charges therein, a crank shaft, a single lobe cam fixed to the crank shaft for actuating the devices, a multiple lobe cam for actuating the devices rotatably associated with the crank shaft, an air valve actuating cam, reduction gearing between the crank shaft and the air valve actuating cam, a shiftable driving connection between the multiple lobe cam and the air valve actuating cam, said driving connection being shiftable into two positions to place the multiple cam lobes in effective or ineffective relation with the injection devices, manually operable means for shifting the driving connection, and spring means opposing the manual movement of the driving connection.

4. In a compression-ignition engine, a pressure injection device for introducing atomized liquid fuel into compressed air charges in the engine, a crank shaft, a single lobe cam for actuating the device fixed to the crank shaft, a multiple lobe cam for actuating the device and rotatably associated with the crank shaft, only one of said cams being effective at a time, an air valve actuating cam, a circular flange extending laterally from the air valve actuating cam, said flange having an internal helical spline, a gear fixed to the multiple lobe cam, reduction gearing between the crank shaft and the air valve actuating cam, a sleeve meshing with the gear fixed to the multiple lobe cam and the splined flange of the air valve actuating cam, and manual means for moving the sleeve axially.

5. In a compression-ignition engine, a pressure injection device for introducing atomized liquid fuel into compressed air charges in the engine, a crank shaft, a single lobe cam for actuating the device fixed to the crank shaft, a multiple lobe cam for actuating the device and rotatably associated with the crank shaft, only one of said cams being effective at a time, an air valve actuating cam having a helical spline, a gear fixed to the multiple lobe cam, reduction gearing between the crank shaft and the air valve actuating cam, a sleeve member meshing with the gear fixed to the multiple lobe cam and having a helical spline meshing with the helical spline on the air valve actuating cam, a yoke associated with the sleeve, manually operable means connected to the yoke for moving the sleeve axially in one direction, and a spring associated with said means for moving the yoke in the opposite direction.

6. In a compression-ignition engine, a pressure injection device for introducing atomized liquid fuel into compressed air charges in the en-

engine, a crank shaft, a single lobe cam for actuating the injection device fixed to the crank shaft, a multiple lobe cam for actuating the device and rotatably associated with the crank shaft, only one of the fuel injection cams being effective at a time, an air valve actuating cam having a helical spline, a gear fixed to the multiple lobe cam, reduction gearing between the crank shaft and the air valve actuating cam, a sleeve 5 member meshing with the gear fixed to the multiple lobe cam and having a helical spline meshing with the helical spline on the air valve actuating cam, a yoke associated with the sleeve, a manually operable rod for moving the yoke to cause axial movement of the sleeve, and a spring associated with the rod to exert pressure against movement of the rod. 10

7. In a compression-ignition engine, a pressure injection device for introducing liquid fuel into compressed air charges in the engine, a crank shaft, a cam for actuating the injection device to introduce fuel into the air charges, an air valve actuating cam, reduction gearing connecting the air valve cam with the crank shaft, a driving connection between the two cams including an axially movable sleeve helically splined between the cams, the axial movement of the sleeve rotating the fuel cam relative to the air cam, a spring for holding said sleeve in one extreme axial position, and manually operable means for moving and holding the sleeve in its other extreme axial position. 20

8. In a compression-ignition engine, a pressure injection device for introducing liquid fuel charges into compressed air charges in the engine, a crank shaft, a cam for actuating the injection device, an air valve actuating cam, a gear fixed to the injection device actuating cam, reduction gearing intermediate the crank shaft and the air valve actuating cam, an axially movable driving sleeve helically splined with the gear fixed to the cam and helically splined to the air valve actuating cam, said sleeve being movable axially to change the relation of the fuel injection device actuating cam angularly of the crank shaft, and manually operable means associated to shift the sleeve in an axial direction. 30

9. In a compression-ignition engine, a pressure injection device for introducing atomized liquid fuel into compressed air charges in the engine, a crank shaft, a single lobe cam fixed to the crank shaft in a relation to actuate the injection device, 40

a multiple lobe cam for actuating the device, said multiple lobe cam being rotatably associated with the crank shaft adjacent the fixed cam, an air valve actuating cam, reduction gearing between the crank shaft and the air valve actuating cam, a driving connection between the air valve actuating cam and the multiple lobe cam including an axially movable sleeve helically splined to the air valve cam and to the multiple lobe cam, the axial movement of the sleeve rotating the multiple lobe cam to place the lobes thereof in advance of or behind the fixed cam lobe whereby they are in effective or ineffective relation with the fuel injection device, manually operable means for moving the sleeve axially, and spring means opposing the manual movement of the sleeve. 45

10. In a compression-ignition engine, a pressure injection device for introducing atomized liquid fuel into compressed air charges in the engine, a cam for actuating the fuel injection device, an air valve actuating cam, mechanism driving the air valve actuating cam from a moving part of the engine, driving mechanism between the cams including an axially movable sleeve helically splined to the air valve cam, manually operable means for shifting the sleeve, and spring means opposing the manual shifting of the sleeve. 50

11. In a multi-cylinder combustion engine of the compression-ignition type, a pressure injection device associated with each cylinder for introducing atomized liquid fuel into compressed air charges in the cylinders, a crank shaft, a cam fixed to the crank shaft to actuate the devices substantially at the highest compression of the air charge, a slower driven cam for actuating the injection devices in advance of the fast cam injection, only one of the cams being effective at a time and the lobe portion of the advanced cam masking the lobe portion of the retarded cam from operative engagement with the injection devices, an air valve operating cam, means for driving the slower cam from the air valve cam including an axially adjustable sleeve in helically splined relation with the air valve cam, a manually operable control member associated to axially move the sleeve to shift the slower cam angularly into retarded position relative to the fast cam, and automatic means for urging the control member in a position to maintain the slower cam in advanced relation relative to the fast cam. 105 110 115 120 125
